DENTAL WASTE RECEPTACLE BASE OR SIMILAR ARTICLE

James W. Benfield, 60 Pinewood Road,
Hartsdale, N.Y.

Filed Feb. 19, 1965, Ser. No. 83,895

Term of patent 14 years

(Cl. D24—1)

FIGURE 1 is an isometric view of a dental waste receptacle base or similar article, showing my new design; and FIGURE 2 is a bottom plan view thereof.

The broken lines are shown for illustrative purposes only.

I claim:

The ornamental design for a dental waste receptacle base or similar article, substantially as shown and described.
